UNITED STATES PATENT OFFICE

2,065,682

COW TAIL HOLDER

George Eugène Fotel, Waterville, Maine

Application February 3, 1936, Serial No. 62,185

5 Claims. (Cl. 119—105)

This invention relates to devices for holding the tail of a cow while the cow is being milked and which will effectively prevent the switching of the cow's tail.

5 Further in accordance with the present invention means is provided whereby the tail of two cows may be effectively held against switching while one of the cows is being milked.

The invention together with its objects and 10 advantages will be best understood from a study of the following description taken in connection with the accompanying drawings wherein:

Figure 1 is a view illustrating the application of the invention.

15 Figure 2 is a perspective view of the invention.

Referring to the drawings by reference numerals it will be seen that in accordance with the present invention there is provided a substantially U-shaped member 5 formed of resilient wire or other suitable material adapted to be disposed across the back of the dairyman. At one end thereof the member 5 is forked as at 6 and the forked end has hinged thereto as at 7 a strap 8 that is adapted to extend across the front of the body and is equipped with a hook 9 to engage an eye 10 in the second end of the member 5 whereby to provide a complete waist encircling device which can be quickly and 30 readily placed around the body of the dairyman as shown.

An apron 11 formed of any suitable material and of a suitable shape and size is provided for disposition upon the lap of the dairyman and 35 said apron is equipped with a suitable strap means 12 whereby the apron may be loosely connected with the member 5.

Further in accordance with the present invention there is provided a substantially U-shaped member 13 formed of resilient wire or other suitable material which is adapted to straddle a leg of the dairyman as shown. The member 13 is connected through the medium of lengths of rope 14 and 15 with the end of the strap 12 secured to 45 the apron 11.

The member 13 serves to hold in proper position a clamping device 16 which is adapted to be clamped on to the tail T of one of the cows, namely the first of two cows that is to be milked (see Figure 1).

50 The clamp 16 does not form the essence of the present invention, I preferably employ a clamp as shown and which is identical with the type of clamp illustrated in Patent No. 1,867,552, the only 55 alteration made in the clamp being the provision

of a thumb rest 17 and a forefinger rest 18 which facilitates opening the clamp incidental to the placing of the clamp on, or a removal of the clamp from the cow's tail. Also the clamp 16 is characterized by having the jaw 19 thereof free of any projection so that the tail of the cow will drop, by its own weight, from between the jaws of the clamp when said jaws are spread apart incidental to a releasing of the clamp from the tail.

10 In connection with the above it will be noted that the member 13 has a part thereof trained between the parts of the clamp in a manner to assist in holding the clamp in the position clearly shown in Figure 1 and with one part of the 15 clamp confined between one side of the member 13 and the leg of the wearer.

Suitable lengths of rope or other flexible material 20 are attached at one end to the clamp 16 at spaced points on the clamp and these pieces 20 are also secured in any suitable manner at 20 one end to the strap 12 as clearly shown in Figure 2.

Also pivoted to the fork 6 of the member 5 at the hinge 7 is an oblong frame 21 of wire or other suitable material to the free end of which 25 is suitably secured a short strap 22. To the free end of the strap 22 is secured in any suitable manner a clamp 23 adapted to hold the tail T' of the second cow to be milked as shown in Figure 1.

Clamp 23 is identical with the clamp disclosed 30 in the hereinbefore referred to patent with the exception that in this form of the invention clamp 23 on one side thereof is provided with a bracket 24 carrying a pulley 25 over which is 35 trained an end portion of an anchoring rope or the like 26. Rope 26 is secured at one end as at 27 to the member 5 while its opposite end is trained through the coil 28 of clamp 23 and over the pulley 25 being secured to the side of the clamp 23 opposite to the pulley 25 as at 29.

40 In connection with the above it will be noted that rope 26 is so associated with the clamp 23 that a pull thereon will tend to spread the jaws 23a, 23b of the clamp apart for effecting a substantially automatic release of the clamp.

45 From the above it will be apparent that when the first cow has been milked the operator manually opens clamp 16 to release the tail T of the first cow. As the operator then walks away from the cow a pull will be exerted on the cable 50 26 for effecting an opening of the clamp 23 to release the tail T' of the second cow. Further it is to be understood that strap 22 is of rubber or other suitable elastic material and will stretch sufficiently to permit the rope 26 to come into 55

play for automatically opening the clamp 23 in the manner above stated.

Having thus described the invention, what is claimed as new is:

- 5 1. In a device of the character described, a body encircling device, an apron, strap means connecting the apron with the body encircling device, a cow tail clamp, flexible elements connecting said clamp with said strap means, a resilient leg encircling member having a part thereof passing between portions of said clamp for securing the clamp in proper position relative to the leg of a milker, and flexible elements connecting said leg encircling member with said strap means.
- 10 2. In a device of the character described, a body encircling device, an apron, strap means connecting the apron with the body encircling device, a cow tail clamp, flexible elements connecting said clamp with said strap means, a resilient leg encircling member having a part thereof passing between portions of said clamp for securing the clamp in proper position relative to the leg of a milker, flexible elements connecting said leg encircling member with said strap means, an elongated member hinged at one end to the body encircling device, a second cow tail clamp, an elastic element connecting the second clamp with said elongated member, and means connected with the body encircling member and the second clamp and adapted, when placed under tension, to effect an opening of the second clamp.
- 15 3. In a device of the character described, a waist encircling member, an elongated member hinged at one end to the waist encircling member,

a cow tail clamp, an elastic member connecting said clamp with said elongated member, and a flexible element connected at one end with the waist encircling member, and at the opposite end with said clamp.

4. In a device of the character described, a substantially U-shaped member adapted to be disposed across the back of the milker, a strap hinged at one end to one end of said U-shaped member and adapted to extend across the front of the milker, interengaging means on the free ends of said U-shaped member and said strap for securing the strap and U-shaped member about the body of the milker, a pair of cow tail clamps, and connections between said clamps and said U-shaped member.

5. In a device of the character described, a substantially U-shaped member adapted to be disposed across the back of the milker, a strap hinged at one end to one end of said U-shaped member and adapted to extend across the front of the milker, interengaging means on the free ends of said U-shaped member and said strap for securing the strap and U-shaped member about the body of the milker, an elongated frame like member hingedly connected at the end of the U-shaped member connected with said strap, a cow tail clamp, an elastic member connecting said clamp with said frame member, and a flexible member connected at one end with the U-shaped member and having a second end connected with opposite portions of said clamp whereby to effect an automatic opening of the clamp when said flexible member is placed under tension.

GEORGE EUGÈNE FOTEL.
